L. DE FOREST

MEANS FOR RECORDING AND REPRODUCING SOUND

Original Filed Sept. 18, 1919

INVENTOR
See de Forest
BY his ATTORNEY
Samuel E. Darby

UNITED STATES PATENT OFFICE.

LEE DE FOREST, OF NEW YORK, N. Y., ASSIGNOR TO DE FOREST PHONOFILM CORPORATION, OF JERSEY CITY, NEW JERSEY, A CORPORATION OF DELAWARE.

MEANS FOR RECORDING AND REPRODUCING SOUND.

Original application filed September 18, 1919, Serial No. 324,683. Patent No. 1,446,246, dated February 20, 1923. Divided and this application filed November 11, 1920. Serial No. 423,276.

To all whom it may concern:

Be it known that I, LEE DE FOREST, a citizen of the United States, and a resident of New York, in the county and State of New York, have invented a certain new and useful Improvement in Means for Recording and Reproducing Sound, of which the following is a specification.

This invention relates to making a record 10 of sound waves suitable for reproduction from the record so made and is directed to the subject-matter divided from my co-pending application U. S. Serial No. 324,683, filed September 18th, 1919, issued as Patent

15 No. 1,446,246, Feb. 20, 1923.

The object of the invention is to provide an electrically controlled means for recording sound.

A further object of the invention is to provide 20 electrically controlled means for photographically recording sound.

Further objects of the invention will appear more fully hereinafter.

The invention consists substantially in the 25 construction, combination, location and relative arrangement of parts, together with the novel methods employed in accordance therewith, all as will be more fully herein-after set forth, as shown by the accompanying drawings and finally pointed out in the 30 appended claims.

Referring to the drawings:—

The single figure illustrates a sound recording arrangement embodying my invention.

In my co-pending application from which the subject-matter of this present case is divided, I have shown and described means 40 for recording sound waves upon a photographic film, such as an ordinary film employed in motion picture photography, and I have therein set forth and have described that a source of light may be directly controlled in the intensity, pitch and volume of 45 sound in such a manner that the fluctuations caused by sound waves in the intensity of light emitted from the source may be photographed upon the film.

In accordance with my present invention 50 I employ a small arc lamp 52, preferably consisting of two heavy tungsten ball electrodes 50 and 51, separated by a small gap, for example, 0.5 millimeter, mounted in the small vessel 52, either evacuated or filled

with some gas, such as nitrogen, mercury vapor, etc., to make the light from such arc as rich as possible in ultra violet rays. The light rays from the arc lamp pass through the lens 3 in the usual well known manner and in addition thereto, if desired, through 60 a color filter 4, which color filter is preferably of a dark blue, as I have found that the best results of recording sound waves photographically are thus secured. A photographic film 7 is passed by the lens and film 3 and 4 respectively in the usual well known manner and the light emanating from the lamp is recorded on the film, preferably in the nature of a minute ray obtained from a pin point aperture or focused 70 to a point by a lens. I energize the arc lamp 52 from a source of high frequency current, the frequency of which must be well above the audible limits and modulate the high frequency currents supplied the arc lamp with 75 alternating or pulsating currents set up by and in accordance with sound waves. For example, but to which I do not desire to be limited or restricted, the high frequency currents may be supplied to the arc lamp by 80 the oscillation system illustrated, wherein the oscillation is shown at 60 and comprises the usual plate electrode 61 and grid electrode 62 interposed between the plate electrode and the filament electrode 63, which filament 85 electrode is heated in the usual well known manner. The grid and plate electrodes are connected by an oscillating circuit including transformer coil 64, which is inductively associated with the transformer coil 65 connected at its terminals to the respective balls 50 and 51 of the small arc lamp 52. Condensers 66 are shunted around the inductance 64 and a tap connection 67 is provided between the oscillating circuit 90 thus formed and the filament electrode 63 including therein an impedance coil 68 and a source of current 69, preferably shunted by a condenser 70. An impedance coil is likewise interposed between the source 95 69 and the filament electrode. The foregoing is briefly a well-established and now a 100 well-known form of high frequency generation circuit forming the subject-matter of separate patents and applications. The alternating or pulsating currents produced by the microphone 5, which is included in circuit with a current source 6 and one coil 105 17

of a transformer, the other coil 18 of which is included in the input circuit of an audion amplifier 90, and thus amplified are supplied by the output circuit of the audion amplifier 90 to the transformer coil 91 included therein, and thence to the transformer coil 92 included in the grid filament circuit of the oscillion 60, thereby effecting a modulation of the high frequency oscillations generated by 10 the balance of the oscillion systems, and the modulated high frequency oscillations vary the degree of brilliancy of light emitted from the arc light by the unmodulated high frequency currents, which variations are proportional in every respect to the original modulating audible frequency alternating or pulsating currents in the microphone circuit. The application of the foregoing principles are many and while I have shown and will 20 now described its application to motion picture photography, to thereby obtain a talking moving picture, I wish it to be understood that I do not desire to be limited or restricted in this respect as this particular 25 application has been selected for the purposes of illustrating the invention involved.

It will thus be apparent that I have provided means which will enable making a permanent record not only of plays but of 30 all talking, singing, or other sound wave producing parts of the plays and enable the reproduction of the same with perfect synchronism inasmuch as they are on the same record or film in proper relation relative to 35 each other. In the drawing I show diagrammatically at 10 a motion picture camera through which the motion picture film 7 passes intermittently in the usual well known manner. I provide a suitable loop 40 11 in the passage of the film and on one side of the loop I subject the film to the sound controlled light rays, the sound for controlling which is produced by the actors, musicians, or the like, which are being 45 photographed. The loop which is provided between the sound recording devices and the camera or light recording devices is to enable the film 7 to pass continuously by the lens 3 as distinguished from the intermittent feed of the film past the camera aperture 3^a for the obvious reason of maintaining the sound record as a continuous record. The relative speed of travel of the 50 film 7 past the sound lens 3 and past the camera aperture 3^a can easily be regulated in any well known manner, such as at present employed in the motion picture photography art for making and maintaining speed loops, it being understood that a similar loop is maintained in the film when a 55 reproduction of the record thereon is obtained.

Many modifications and changes in details will occur to those skilled in the art 60 without departing from the spirit and scope

of my invention as defined in the claims, and I therefore desire to have the foregoing description and the illustrations used in connection therewith regarded in the illustrative sense rather than in a limiting sense. 70

Having now described and illustrated my invention and having set forth and shown a structure embodying the principles thereof, what I claim as new and useful and of my own invention, and desire to secure by Letters Patent is:—

1. The combination with an alternating current lamp, means for continuously supplying an alternating current to said lamp the periodicity of which is above the audible limits to effectively maintain said lamp a constant source of light, and sound controlled means for varying said current. 80

2. The combination with an alternating current lamp, means for continuously supplying an alternating current to said lamp the periodicity of which is above the audible limits to effectively maintain said lamp a constant source of light, and means for varying the alternating current so supplied by and in accordance with sound controlled alternating currents the periodicity of which is within the audible limits. 90

3. The combination with an alternating current lamp, an oscillion for supplying high frequency oscillations to said lamp to effectively maintain said lamp a constant source of light, and sound controlled means for modulating said high frequency oscillations. 100

4. The combination with an alternating current lamp, an oscillion for supplying high frequency oscillations to said lamp to effectively maintain said lamp a constant source of light, and means for modulating said high frequency oscillations by and in accordance with sound waves to produce corresponding modulation in the light emitted by said lamp. 105

5. Means for photographically recording the sound waves, comprising an electrically lighted lamp, means for constantly supplying high frequency oscillating current to said lamp to light the same, means for controlling said lamp by and in accordance with sound waves, and means for directing the light from said lamp to a sensitized element. 110

6. Means for photographically recording the sound waves, comprising an electrically lighted lamp, means for constantly supplying high frequency oscillating current to said lamp to light the same, means for controlling said lamp by and in accordance with low frequency currents, and means for directing light rays from said lamp to a sensitized element. 120

7. Means for photographically recording sound waves comprising an enclosed luminous gas discharge device, means for con-

stantly maintaining said device effectively luminous, and means for varying the luminosity of said device by and in accordance with sound waves, and means for directing the light from said device to a sensitized element.

8. Means for photographically recording sound waves comprising an enclosed luminous gas discharge device, means for constantly maintaining said device effectively luminous, and means for varying the luminosity of said device by telephone currents, and means for directing the light from said device to a sensitized element.

9. The method of photographically recording sound which comprises varying the luminosity of an effectively constantly luminous enclosed gas discharge device by and in accordance with sound waves. 15

10. The method of photographically recording sound which comprises varying the luminosity of an effectively constantly luminous enclosed gas discharge device by and in accordance with telephonic currents. 20

In testimony whereof I have hereunto set my hand on this 3d day of November, 25
A. D. 1920.

LEE DE FOREST.
